UNITED STATES PATENT OFFICE

FRANK B. ALLEN, OF LOWER MERION TOWNSHIP, MONTGOMERY COUNTY, PENNSYLVANIA, ASSIGNOR TO THE ALLEN-SHERMAN-HOFF COMPANY, A CORPORATION OF PENNSYLVANIA

CONTROL MEANS FOR CENTRIFUGAL PUMPS

Application filed May 31, 1929. Serial No. 367,588.

This invention relates to centrifugal pumps and is particularly concerned with a centrifugal pump which can be automatically controlled in a manner to prevent injury to the pump during its operation.

In pumping liquids containing substances injurious to parts of the pump, including the impeller shaft bearings, it has been proposed to provide in the pump casing a plurality, for example, two communicating chambers and so to construct the pump that pressure differentials will be created between the respective chambers so that non-injurious fluid will flow from one chamber into another chamber through which liquid containing injurious material is passing.

This proposal is dependent for complete success on the provision of an adequate supply of liquid substantially free from injurious material to the chamber in which the higher pressure is created; and where this supply is subject to failure the foregoing proposed construction may not prevent ingress of liquid carrying injurious substances to the parts of the pump from which it is desired that they be excluded.

Accordingly by the present invention I have provided means for automatically de-energizing the pump driving means, which de-energizing means operates when the pressure differential between the communicating chambers falls below a predetermined amount.

In the drawing accompanying and forming a part of this specification the figure is a side elevational view, partly diagrammatic and partly in section showing one form of apparatus embodying my invention.

In the drawing 1 designates a base of any suitable construction upon which is mounted an electric motor 2, a shaft support 3 and a pump casing 4. A shaft 5 attached to the motor 2 extends through suitable bearings 6 carried by the member 3 and projects into the casing 4 of a centrifugal pump. The shaft 5 carries within the casing 4 an impeller 7 provided with a hub portion 8 attached to the shaft 5, a disc 9 preferably integral with the hub 8 and impeller blades 10 disposed on one side of the disc 9. A disc 11

serves as a cover for blades 10 and its outer surface is disposed closely adjacent to the lateral side wall 12 of the casing 4. The disc 9 also carries auxiliary blades 13 preferably integral therewith and disposed on the side 55 thereof opposite to the blades 10. The disc 9 at its periphery forms with the adjacent portion of the casing an annular passage between the chamber 14 in which the auxiliary blades 13 are disposed and the main 60 chamber 15 in which the main blades 10 are disposed.

The side wall 16 or engine side plate of the casing 4 is provided with a stuffing box 17 through which the shaft 5 extends and in which packing material 18 is disposed and held in position by a packing gland 19. The wall 16 forms a chamber 20 about the shaft and its bearing 21, which chamber communicates with the chamber 14 and has a conduit 22 leading thereinto for supplying liquids substantially free from injurious materials to the chambers 20 and 14.

The side plate 12 is provided with the suction inlet opening 23 for entry of liquids containing injurious materials to the chamber 15 and casing 4, the chamber 15 having a suitable outlet or discharge opening (not shown).

Conduits 24 and 25 communicate respectively with chambers 15 and 14 and with 80 suitable means for de-energizing motor 2. The means shown for de-energizing the motor consists of a valve 26 having a diaphragm 27 therein which divides the interior of the valve 26 into a chamber 28 which is in communication with conduit 24 and a chamber 29 in communication with conduit 25. A spring 30 in chamber 28 surrounds a rod 31 and is compressed between the diaphragm 27 and one wall of the valve 26. The rod 31 projects through the valve and is pivotally connected to an arm 32 which constitutes a part of the electrical circuit through which current may flow to the motor 2. This circuit includes lines 33 and 34 and a cutout switch 35.

The operation of the above described embodiment of my invention is as follows:

In starting the pump liquids substantially free from injurious substances are admitted 100

under pressure through conduit 22 into chambers 20 and 14. When the pressure differential between chambers 14 and 15 reaches the predetermined amount the diaphragm 27 will be moved to compress spring 30 and move arm 31 to complete the electrical circuit from the switch 35 which has previously been closed through the lines 33 and 34 to the motor, whereupon the motor 2 will be energized and the impeller 7 will be rotated.

The auxiliary blades 13 will maintain the pressure differential above the predetermined minimum so long as the supply of liquid through conduit 22 continues in a sufficient amount, but when that supply is diminished below a certain amount or cut off completely the pressure in chamber 14 will drop and if the drop is sufficient the spring 30 will move the diaphragm 27 and pull rod 31 toward the valve 26 with resultant interruption of the electrical circuit due to the opening switch of which arm 32 is a part. The pump will then stop before a sufficient amount of liquid containing injurious material has penetrated into the chamber 14 and bearing 21 to injure the bearing.

Having thus described my invention so that those skilled in the art may be enabled to practice the same, what I desire to secure by Letters Patent is defined in what is claimed.

What is claimed is:

1. The combination with a centrifugal pump having a plurality of communicating chambers, means for driving the pump and means for creating a pressure differential between the said chambers, of means for automatically de-energizing the pump driving means when the said pressure differential drops below a predetermined amount.

2. In combination with a centrifugal pump having a main pumping chamber, an impeller in said main chamber, an auxiliary chamber communicating with said main chamber, an auxiliary impeller in said auxiliary chamber and means for driving said impellers, of means for creating a pressure differential between said chambers and means for automatically de-energizing the pump driving means when said pressure differential drops below a predetermined amount.

3. The combination of a centrifugal pump having a main pumping chamber, an impeller in said main chamber, an auxiliary chamber communicating with said main chamber, means for supplying liquid free from injurious material to said auxiliary chamber, an auxiliary impeller in said auxiliary chamber, said impellers and chambers being adapted to create a pressure differential between said chambers, means for driving said impellers, and means for automatically de-energizing the pump driving means when the said pressure differential drops below a predetermined amount.

4. The combination of a centrifugal pump

having a plurality of communicating chambers, impellers in said chambers, means for driving the pump, separate fluid inlets leading to said chambers, means for creating a pressure differential between said chambers and means for stopping said pump driving means when said pressure differential reaches a predetermined value and starting said pump driving means when the pressure differential reaches another predetermined value.

5. The combination of a centrifugal pump having a main pumping chamber and an auxiliary chamber communicating with said main chamber, impeller means in said chambers for creating a pressure differential between said chambers, means for driving said pump, means for controlling the operation of said driving means and means responsive to changes in said pressure differential for actuating said controlling means.

In testimony whereof I hereunto affix my signature this 27th day of May, 1929.

FRANK B. ALLEN.
